COFFEE VENDING MACHINE CABINET

Elmer C. Johnson, Kansas City, Mo., assignor to The Vendo Company, Kansas City, Mo., a corporation of Missouri

Application December 8, 1958, Serial No. 53,673

Term of patent 14 years

(Cl. D52—3)

Fig. 1 is a perspective view of a coffee vending machine cabinet, showing my new design; and

Fig. 2 is an enlarged, fragmentary sectional view taken on line 2—2 of Fig. 1.

The undisclosed side of the vending machine is substantially like the side shown and the top and rear are plain.

I claim:

The ornamental design for a coffee vending machine cabinet, as shown and described.
